(57) **CLAIM**

I claim as my invention the ornamental design for a sphere mold, as shown and described.

DESCRIPTION

FIG. 1 shows a perspective view of the sphere mold; FIG. 2 shows a first, side view of the sphere mold when it is in a closed position where the opposite side is to the same as the side shown;

FIG. 3 shows a top of the sphere mold when it is in a closed position;

FIG. 4 shows a second side view of the sphere mold when it is in a closed position where the opposite side is the same as the to the side shown;

FIG. 5 shows a top view of the sphere mold when it is in an open position;

FIG. 6 is a side view of the sphere mold when it is in a closed position;

FIG. 7 is a sectional view of the sphere mold taken from line 7-7 of FIG. 6;

FIG. 8 is an exploded view of the sphere mold; and, FIG. 9 is a bottom view of the sphere mold.

1 Claim, 8 Drawing Sheets
